UNITED STATES PATENT OFFICE.

JAMES A. LAWTON, OF MIDDLETON, CONNECTICUT.

MEDICAMENT CARRIER.

Application filed October 23, 1926. Serial No. 143,685.

This invention relates to a cleaner and medicament carrier for use in cleaning the teeth, and has for an object to provide an improved device of this character which is 5 adapted to be inserted into the interproximal spaces between the teeth and used for cleaning the adjacent surfaces of the teeth and gums, and will have pockets or containers for carrying the cleaning material or medicament, which will be carried to the proper 10 surface by the use of the cleaner and will cooperate therewith to clean or medicate the surfaces.

With the foregoing and other objects in 15 view, I have devised a construction, several forms of which are shown as examples in the accompanying drawing forming a part of this specification. In this drawing,

Fig. 1 is a longitudinal section through 20 one form of my improved carrier and cleaning element.

Fig. 2 is a transverse section thereof through the wall between two adjacent pockets.

Fig. 3 is a longitudinal section through 25 the cleaning carrier showing a somewhat different construction.

Fig. 4 is a transverse section thereof through the wall of two adjacent pockets.

Fig. 5 is a partial side elevation and 30 partial longitudinal section through the carrier and cleaner showing a still different construction.

Fig. 6 is a transverse section taken 35 between two adjacent pockets.

Fig. 7 is a longitudinal section through a single cleaning element, and

Fig. 8 is an end elevation thereof.

In the drawings I have shown several 40 forms of the device but all of which operate in practically the same manner. It will be understood, of course, that the drawings are on a greatly enlarged scale and also are exaggerated to more clearly disclose the construction. In the form shown in Figs. 1 and 2 the device comprises a flexible tube of suitable material, preferably rubber, and it is formed with one or more pockets or containers 10 at suitable spaced intervals.

50 These pockets may be formed in various ways, but in the form shown the walls of the tube between the pockets are pressed together, as shown at 11, and either vulcanized so that they form isolated pockets or they 55 may be cemented together, and the pockets are filled with a cleaning material 12, which

may be merely a cleaning material, a medicament or the like, and I have used the term "cleaning material" throughout the specification and claims in its broader sense as meaning merely a cleaning material, a medicament, or a combination of the two, or the like; and it also may be used in various forms, such as a liquid, a paste or a powder. It is preferred that the carrier 60 be prepared in strips of considerable length so as to be wound on a support or folded and marketed in a suitable container. The closed walls 11 between adjacent pockets, or at suitable intervals to leave one or more 65 pockets to a section, are provided with a weakened portion 13 so that the sections may be easily torn apart for use. In Fig. 1 the weakened portions are so spaced as to provide two pockets to a section, but there 70 may, of course, be only one or there may be any number desired. The weakened tearing off portion may be provided by notching the tube on opposite sides as shown at 13, or there may be a series of perforations to 75 secure the same effect. It is also preferred that one wall of the tube be weakened so that one wall of the pocket is weaker than the other, this being shown as the upper 80 wall 14 in Figs. 1 and 2, so that when the element is used this insures that this wall of the pocket will be broken to release the cleaner or medicament. In use a desired length of the element is separated from the strip, either by tearing or cutting it off, 85 and it is then inserted between the teeth and it is then inserted between the teeth into the interproximal space. The wall of the pocket may then be broken either by pressing the pocket with the finger against the teeth or by drawing the pocket against 90 the teeth. As the wall of the pocket is ruptured the cleaning material is forced out onto the teeth, the gums, and the carrier, and as the carrier is drawn back and forth it will carry this cleaner against the surfaces of 95 the teeth and the gums and will rub it against the surfaces, so that the cleaning operation is performed not only by the cleaning material but it is also assisted by the rubbing or frictional action of the carrier 100 against these surfaces.

In the form shown in Figs. 3 and 4 the carrier is made up of two flat flexible strips 15 and 16 of suitable material, such as rubber, which are cemented or otherwise secured together as indicated, to provide spaced 110 pockets or containers 17 for the cleaner or

medicament 12. The walls between these containers or pockets may be weakened at 18 the same as in the forms shown in Figs. 1 and 2, to facilitate separating the carrier 5 into sections of the desired length for use in cleaning the teeth. This construction is used the same as the first form, and one of the flat strips, as the upper strip 16, will be somewhat thinner or weaker as indicated on 10 the drawing, so that as the pocket is pressed against the teeth this wall will be ruptured to release the cleaning material while the other wall will have sufficient strength for rubbing the material against the surfaces to 15 be cleaned and for cleaning them by frictional action as indicated above. Also the surface of the material may be corrugated to increase its frictional value and its capacity for holding the cleaning material. 20 and carrying it to the surfaces to be cleaned. If desired the upper wall 16 may be made of some material which will be dissolved by contact with the saliva in the mouth to thus release the cleaning material. 25 In the form shown in Figs. 5 and 6 the construction is practically the same as that shown in Figs. 1 and 2, except that the walls of the carrier 19 between the pockets or containers 20 instead of merely being pressed together as shown in Fig. 1, are twisted together as indicated at 19, and either pressed together, fused or cemented to form separate 30 pockets or containers. This makes a somewhat better cleaning element as the spiral surfaces or edges formed by this construction carries the cleaning material to the cleaning surfaces and also has a somewhat more effective cleaning action on the 35 faces. 40 In Figs. 7 and 8 the construction is practically the same as shown in Figs. 1 and 2, but, however, shows merely a single section having a single pocket or container 21 to the strip, for holding the cleaning material 45 12. The sides of the tube are pressed together, as shown at 22, to close the opposite ends of the pocket. This form is intended 50 to be made in separate sections and dispensed in containers holding any desired number of these sections, and it will, of course, be understood the section may have 55 one or more pockets or containers as desired. 60 My improved carrier and cleaning element will provide a means for the individual person as well as for the dentist in operation for effectively and quickly cleaning interproximal spaces between the teeth and the curved 65 margins of the teeth by friction, which has not been hitherto available. It will effectively remove food débris and other solid matter from between the teeth, and will discover if there are faulty or imperfect fillings and obscure cavities between the teeth. This carrier can be used for carrying other 70 antiseptics or medicinal fluids, pastes or solids

between the teeth for treatment of diseased conditions of the teeth, gums, or surrounding tissues. If the carrier is made of rubber this cleaning material or medicament should be of a material which is not affected 70 by contact with the rubber or will cause deterioration of the rubber, or the interior surface of the rubber may be coated with some material which would not affect or be affected 75 by the cleaning material.

For ordinary use it is believed the pockets should be approximately about a quarter of an inch long and the pressed spaces between them about one-half inch, although of course, it will be understood that this may be varied 80 as is found desirable and necessary. It is preferred that the pockets shall contain the cleaning material, such as a soluble antiseptic or dentifrice, in the form of a paste as that is the most common form which is used 85 at the present time, but I am not, of course, limited to the use of a paste as it may be in the form of a liquid or powder, and the completed article is dispensed in a sanitary container for easy accessibility by the individual user. As indicated above the use 90 is very simple, as it is used by being passed between the teeth to the interproximal space and then drawn back and forth against the surfaces, the pockets containing the cleaner being broken by being drawn against the 95 the teeth with the fingers, thus depositing this material on the surfaces to be treated, or onto the carrier which then wipes it onto the teeth or the surface being treated. The 100 elasticity of the rubber makes it possible to regulate pressure between the teeth and on each tooth. The solubility of the medicament renders the fluids of the mouth comparatively sterile for a short time, thus 105 creating the desirable clean conditions. The carrier may be a solid piece of rubber with the medicament on it, or the pockets for the medicament may be formed on such a piece 110 of rubber.

Having thus set forth the nature of my invention, what I claim is:

1. As an article of manufacture, a dental cleaner which comprises a carrier adapted to be drawn into the interproximal spaces 115 between the teeth and having a pocket carrying a medicament or cleaning material, a wall of the pocket being adapted to be broken by pressure so that the medicament or cleaning material will be carried by the 120 carrier to the surfaces to be cleaned.

2. A dental cleaning element comprising a flexible carrier adapted to be inserted between the teeth and rubbed against a surface to be cleaned and having a pocket containing a cleaning material, a wall of the pocket being adapted to be broken to deposit the cleaning material on the surface to be cleaned.

3. A dental cleaning element comprising 130

a flexible cleaner and carrier adapted to be inserted in the interproximal spaces between the teeth and carrying a pocket containing a cleaner, a wall of the pocket being adapted to be ruptured to release the cleaner.

4. A dental cleaning element comprising a flexible rubber tube adapted to be inserted in the interproximal spaces between the teeth and having its side walls secured together at spaced intervals to provide a pocket, a cleaning material in said pocket, a wall of the pocket adapted to be ruptured by pressure to release the cleaning material.

5. A dental cleaning element comprising a flexible rubber tube adapted to be inserted in the interproximal spaces between the teeth and having its side walls secured together at spaced intervals to provide spaced

pockets, a cleaning material in said pockets, a wall of the pockets being adapted to be ruptured by pressure to release the cleaning material, and the walls between the pockets having a weakened portion to permit easy separation of the element into separate strips.

6. A dental cleaning element comprising a flexible cleaner and carrier adapted to be inserted in the interproximal spaces between the teeth and carrying a plurality of spaced pockets, a cleaning material in said pockets, and the walls of the carrier between the pockets being provided with a weakened portion to permit easy separation of the carrier into separate sections.

In testimony whereof I affix my signature.
JAMES A. LAWTON.
